TIMING DEVICE FOR INTERNAL COMBUSTION ENGINES

Filed April 17, 1922

Inventor
Orville E. Key

Memphill Attorney

UNITED STATES PATENT OFFICE.

ORVILLE E. KEY, OF LITTLE YORK, ILLINOIS.

TIMING DEVICE FOR INTERNAL-COMBUSTION ENGINES.

Application filed April 17, 1922. Serial No. 553,314.

To all whom it may concern:

Be it known that I, ORVILLE E. KEY, a citizen of the United States, residing at Little York, in the county of Warren and 5 State of Illinois, have invented certain new and useful Improvements in Timing Devices for Internal-Combustion Engines, of which the following is a specification.

This invention relates to improvements in 10 timing devices for internal combustion engines and relates more particularly, to a new and improved contact brush and means for mounting and adjusting the same.

The principal object of my invention is 15 to provide a new and improved contact brush for timers and improved means for mounting and adjusting the same as will provide more efficient and reliable contact, and add to the life of the device and indirectly increase the efficiency of the engine in 20 connection with which it is used.

A further object of the invention is to 25 provide a device of the above character that is simple in construction, strong and durable, and which it is believed may be manufactured at a reasonably low cost.

Various other objects and advantages of 30 my invention will become apparent during the continuance of the following description.

In the drawings:—

Figure 1 is a view in cross-section of a 35 timer of conventional form showing my invention in its preferred embodiment used in connection therewith.

Figure 2 is a view in transverse cross-section taken on line 2—2 of Figure 1.

Figure 3 is a view in transverse cross-section taken on line 3—3 of Figure 1.

Figure 4 is a view partly in cross-section 40 and partly in elevation taken on line 4—4 of Figure 2.

Figure 5 is a view in cross-section taken on line 5—5 of Figure 3.

The timer proper shown for purposes of 45 illustration consists generally of a casing 10 having mounted therein contact plates 11 insulated with respect to each other as at 12 and conventional binding posts 13. The operating shaft 14 extends into the interior 50 of the casing and is of the usual and ordinary construction.

My invention consists more generally in a casing like carrier 15 arranged over the 55 end of the shaft 14 that projects within the interior of the casing 10, an opening 16

being provided therein to permit the threaded end 17 of the shaft 14 to pass there-thru. The usual securing members 18 are positioned on the threaded end 17 as clearly shown in Figure 4. The carrying member 60 is keyed to the shaft 14 through the medium of a tapered key 19 that is positioned in registering openings 20 and 21 of the shaft 14 and the carrying member 15 respectively, as shown in Figure 3 and is designed to 65 prevent independent operation of the shaft and the carrying member. At one side the carrying member is provided with an offset 22 that is provided with a tapered tubular recess 23 arranged at a substantial right 70 angle with respect to the line of extent of the shaft 14. Upon reference to Figure 3 it will be noted that the recess 23 is open at one end to permit the insertion and removal of certain members while its other end is 75 partly closed although the offset is provided at that point with a constricted opening 24 for the purpose that will presently appear.

The brush proper consists of a normally 80 slightly curved metallic element 25 the curved part of which is adapted to lie in the plane of the contact plate 11 and engage said contact plate when the shaft 14 and the carrying member 15 are turned. 85 One end portion of the brush member is slightly constricted as at 26 and such constricted portion is adapted to lie within the tapered recess 23 of the offset 22 as clearly shown in Figure 3. A tapered locking 90 member 27 is also adapted to be partitioned in the recess 23 and has a threaded shank 28 which projects through the opening 24 of the offset 22. When the locking member 27 is positioned within the recess 23 a nut 95 or other fastening member 29 may be screwed on the projecting end of the shank 28 so as to draw the member 27 inwardly and thereby securely bind the constricted portion 26 of the brush 25 against the wall 100 of the recess. In this way the brush can be securely locked in place and it will be readily noted that the adjustment of the brush by first loosening the locking member 27 can be easily accomplished. 105

When in operation the parts are assembled substantially as shown in Figure 2 so that when the shaft 14 and the carrying member 15 are rotated the brush 25 will be brought in contact with the plate 11 and 110

make and break the electrical circuit in the usual and well known manner. The re-adjustment of the brush may be accomplished so as to compensate for wear on the free end thereof and by reason of the curved construction of the outer end of the brush a better contact with the plate 11 is had so as to increase the efficiency of both the timer and the engine in connection with 10 which it is used. The parts can be readily assembled or dissembled and it will also be noted that the improved carrying member 15 and the brush 25 can be used in connection with the timers of the conventional 15 Ford.

From the foregoing it is believed that the advantages and novel features of my invention will be readily understood and therefore further detailed description is 20 deemed unnecessary.

What is claimed is:

1. The combination with a timer casing and a shaft projecting into the same of a carrying member keyed to said shaft and 25 adapted to operate with said timer casing, an offset on said carrying member provided with a tapering recess extending at right-angles to the extent of said shaft, a brush member having a portion curved in substantially 30 the arc of a circle, a reduced portion on said brush adapted to enter said recess, a tapering locking member in said recess, and means to adjust said locking member to

secure said brush member in place substantially described.

2. A device of the character described comprising in combination with a timer casing of conventional form having one end of a rotatable shaft projecting thereinto of a casing like carrying member carried on 40 said shaft within said timer casing, means to lock said carrying member against independent rotation with respect to said shaft, an offset on said carrying member provided with a tapering recess extending at right-angles to the general extent of the shaft, said recess being open at one end and said offset being provided with a constricted opening at the other end, a brush member having a portion curved in substantially the arc of 45 a circle, a restricted portion on said brush adapted to enter said recess, a tapered locking member adapted to be inserted in said recess, a shank on said locking member adapted to project through said opening, a fastening member arranged on the projecting end of said shank whereby said locking member may be adjusted within 50 said opening to secure the constricted portion of said brush member in a rigid position with respect to said offset substantially 55 as described.

In testimony whereof I affix my signature.

ORVILLE E. KEY.
